UNITED STATES PATENT OFFICE.

VICTOR M. SUMMA, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

HOPPER-DOOR MECHANISM.

1,097,951.

Specification of Letters Patent. Patented May 26, 1914.

Application filed November 20, 1912. Serial No. 732,496.

To all whom it may concern:

Be it known that I, VICTOR M. SUMMA, residing at 915 Olive street, St. Louis, Missouri, and being a citizen of the United States, have invented certain new and useful Improvements in Hopper-Door Mechanism, being for the same invention as that shown in my application Serial No. 559,653, filed May 5, 1910, and of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a fragmentary view, partly in vertical, longitudinal section and partly in side elevation, of a car embodying the features of the present invention. Fig. 2 is a transverse vertical central section taken on a plane indicated by line 2-2 in Fig. 1. Fig. 3 is a diagrammatic view showing a slight modification.

While it is obvious that the present improved door and door operating mechanism are applicable to hopper cars of any type, I find it convenient to illustrate the same as applied to a double hopper car having twin or laterally juxtaposed hoppers.

Referring to the drawings by numerals, 1-1 are the side sheets of the hoppers through which extend transversely arranged rock shafts 2-2, said shafts being journaled in bearings 3-3 fixed to said sheets.

The side sheets of the hopper are spaced apart transversely and extend longitudinally of the car at each side of the twin hoppers and span the space between said hoppers. The hoppers are disposed at each side of the center sills, and said side hopper-sheets serve as supports for the doors or valves employed to close the discharge ports of the hoppers.

There are shown in the accompanying drawings four such side hopper sheets, two of which serve as depending continuations 1 of the supporting side plate girders 1^a of the car, and two inner side hopper-sheets

1^b which serve as depending extensions of the longitudinal hood 4.

The juxtaposed double hoppers are separated by the usual longitudinal hood 4, and each is divided into its two hoppers by transverse hood 5, each hopper being completed by the side sheets 1, and the bottom inclined plates 6-6. Each inclined plate 6 is spaced from the lower edge of the respective side of hood 5, leaving a door-way adapted to be closed by a door 7, comprising an upwardly and inwardly convexed sheet 8, having outwardly turned edge flanges 12 fixed to the segmental sheets 9, which are disposed next adjacent the sheets 1^b referred to. Each sheet 9 tapers away from the hopper, and is flanged along its upper and lower edges and stiffened along its lower edge by a flat bar 11 riveted to the sheet. Plate 8 is flanged at its lower edge 8', and a vertically disposed stiffening plate 13 is arranged intermediate the length of plate 8 with its outer edge flanged and contacting with the plate and riveted thereto. Thus the door 7 is segmental in its general form with its arcuate or convex face exposed toward and normally closing the hopper door-day. It is, of course, obvious that the curvature of such face may be varied when desired, as for instance by forming the same with approximately an involute curve, which, in operation as hereinafter described, would cause the face plate 8 to recede from the lading as it moves upwardly and thus materially lessen the friction thereof. (See Fig. 3).

Each plate 6 underhangs the lower edge 90 of the respective door 7, and is stiffened by an angle 14, which extends continuously across the lower edge of said plates 6, and the lower edge of each transverse hood 5 is also stiffened by an angle 15.

Each door 7 is fixed to its respective shaft 2, the shaft extending through the inner ends of the door plates 9 and the bars 11, and also through the inner end of a bar 16 disposed intermediate the length and width of the door, and extending from the respective shaft 2 to the plate 8 and riveted to plate 13 midway of the length thereof.

The shafts 2 extend continuously through the inner and outer side hopper-sheets 1^b and 1, and the bearings 3 for said shafts are

secured directly to said side hopper-sheets, which sheets depend below the plane of the center sills 19 of the car to provide guides for the load in discharging and also as 5 supports for the door operating mechanism.

The bar 16 of each door is engaged intermediate its length by an operating chain 17 extending upwardly and being fixed to an operating shaft 18 which passes through 10 the side plates of the hopper and through the center sills 19 of the car, the shaft 18 being journaled in bearings 20-20 fixed to the outer side plates of the hopper and to the webs of the center sills. The ends of 15 the shaft 18 are provided with ratchet wheels 21, each adapted to be engaged by a pawl 22 for locking the shaft at times against rotation, the extreme ends of the shaft extending beyond the wheels and being formed with polysided portions 23 for receiving operating tools.

Extending transversely of the car is an I-section 30 which passes through openings in the inner side hopper sheets 1-1 and is 25 connected therewith by means of angle brackets 31 riveted respectively to the said members 1 and 30. Said section 30 is connected with the outer side hopper sheets 1 by means of similar angle brackets 32, the 30 section 30 terminating within said outer side hopper sheets, thus serving as a stiffening member connecting and effectually bracing the said side hopper sheets below the center sills, and the section 30 is connected to the 35 said center sills by rivets 33, Fig. 2.

In operation, assuming the parts to be in position indicated in full lines in Fig. 1, to discharge the load, it is only necessary to apply operating tools to the portions 23 and 40 revolve shaft 18, resulting in taking up chains 17 and thus swinging the doors 7 upwardly on their pivotal mountings to the position indicated in dotted lines in Fig. 1. After the discharge of the lading, the pawls 45 22 are released from their ratchet wheels 21 and the chains paid out as the doors move by gravity to their lower or closed positions. It is to be noted that the underhanging portions of plates 6 afford stops for the doors. 50 To facilitate the discharge of the load, the transverse hoods 5 are of less length longitudinally of the car than the distance between contiguous edges of the inclined sheets 6, thereby providing an increased 55 door opening through which the load will more quickly pass than if the holes were co-extensive with the space between said sheets 6.

The shafts 2 extend through the side hopper-sheets and are spaced apart longitudinally of the car, and the sheets 6 terminate at a considerable distance apart so as to provide a maximum discharge opening for the load and to permit the relatively large doors 65 to come to full open position beneath the

transverse hood 5, which is preferably of only sufficient area to cover and protect the two doors and the door operating mechanism.

What I claim is:

1. A hopper door comprising a convex plate, segmental side plates connected to the ends of the convex plate, a stiffening plate fixed to the convex plate intermediate the length thereof, stiffening bars extending along the lower edges of the segmental plates and fixed thereto, and a bar intermediate the length of the convex plate fixed to the stiffening plate, the ends of said bars 70 75 80 farthest from the segmental plate being adapted to receive a pivotal mounting for the door.

2. In a hopper bottom car, the combination with a hopper of a door for closing the same, comprising a convex plate, segmental plates fixed to the ends thereof and tapering away from the hopper, an intermediate stiffening plate fixed to the convex plate, bars fixed to the end plates and an intermediate bar fixed to the stiffening plate, a 85 90 95 pivot shaft engaging the tapered end of said door, a shaft journaled above the pivot shaft, and flexible means directly connecting said journaled shaft to the intermediate bar of the door.

3. In a hopper car, a hopper comprising a transverse hood, vertical side hopper-sheets and inclined floor sheets, in combination with pivotally movable gravity closing doors supported by said side hopper-sheets, 100 and means extending below said hood through some of the side hopper-sheets for lifting said doors to open position.

4. In a hopper car, a hopper comprising a transverse hood, vertical side hopper-sheets and inclined floor sheets, in combination with pivotally movable gravity closing doors supported by said side hopper-sheets, a center sill, an operating shaft extending through said center sill below said hood, and 105 110 flexible connections from said operating shaft for lifting said doors to open position.

5. In a hopper car, a hopper comprising a transverse hood, vertical side hopper-sheets and inclined floor sheets, in combination with pivoted gravity closing doors rock shafts therefor supported by said side hopper-sheets, a center sill, an operating shaft extending through said sill and supported thereby at a plurality of places below said 115 120 125 hood, and flexible means extending from said shaft to said doors.

6. In a hopper car, a hopper comprising a transverse hood, vertical side hopper-sheets and inclined floor sheets, in combination with gravity closing doors supported by said side hopper-sheets, and a transverse supporting member extending through some of said side hopper-sheets, a center sill, an operating shaft protected by said hood and extending 130

through said sill and said side hopper-sheets, and means connecting said operating shaft and said doors.

7. In a hopper car, a hopper comprising a transverse hood, vertical side hopper sheets and inclined floor sheets, in combination with rock shafts and pivoted gravity closing doors on said rock shafts supported by said side hopper-sheets, center sills spaced apart, an operating shaft supported at intervals by said spaced sills and extending through some of said side hopper-sheets, and means for lifting said doors from said shaft to position below said hood, the shaft and lifting means being protected by said transverse hood.

8. In a hopper car, a center sill, a transversely extending hood, side hopper-sheets and inclined floor sheets coöperating with said hopper-sheets, a shaft supported at a plurality of places by said sill, said shaft being protected by the hood, a gravity closing door pivotally supported on said hopper-sheets, and a flexible connection from the shaft to the door adapted to open the door.

9. In a hopper car, a center sill, spaced side hopper-sheets, spaced inclined floor sheets connected with the hopper-sheets and connected by said hopper-sheets across the space between said inclined sheets, gravity closing doors supported by said inclined floor sheets when the doors are closed, pivot mountings for said doors carried by the hopper-sheets, a shaft supported at intervals by said sill, and a connection between said shaft and the doors adapted to lift the doors to open position.

10. In a hopper car, spaced longitudinally extending side hopper-sheets, a transversely extending hood, inclined floor sheets connected with said hopper-sheets, gravity closing doors pivotally connected with said hopper-sheets intermediate the said floor sheets and adapted to close the opening between the hood and floor sheets, and door opening means protected by said hood.

11. In a hopper car, transversely spaced longitudinally extending side hopper-sheets, inclined floor sheets connected to and spanned by said hopper-sheets, said floor sheets being spaced apart longitudinally of the car, pivoted gravity closing doors positioned intermediate the hopper-sheets and intermediate the inclined floor sheets, rock shafts on which said doors are rockable, means positioned between the doors for moving said doors to open position, and a transversely extending hood protecting the means for moving said doors.

12. In a hopper car, a double twin hopper having parallel inner and outer side hopper sheets, shaft bearings secured to each of said sheets, shafts in said bearings, segmental doors mounted on said shafts, an operating shaft extended through some of said hopper sheets, flexible connections from said operat-

ing shaft to said doors, and a transverse hood adapted to cover said doors when they are in open position.

13. In a hopper car, center sills, a hopper having relatively vertical side hopper-sheets, a door supporting shaft and a door operating shaft above said supporting shaft projecting through said hopper-sheets, a door rockable on said supporting shaft, and a flexible connection from said operating shaft to said door adapted to lift the door.

14. In a hopper car, continuous transversely spaced side hopper sheets, spaced converging inclined floor-sheets secured directly thereto, pivoted doors closing by gravity positioned between said inclined floor-sheets and between said side hopper sheets and supported in closed position by all of said sheets, and means for lifting said doors to open position.

15. In a hopper car, continuous transversely spaced side hopper-sheets, spaced converging inclined floor-sheets secured directly thereto, pivoted doors closing by gravity positioned between said inclined floor-sheets and between said side hopper-sheets and supported in closed position by all of said sheets, means for lifting said doors to open position, and a transversely extending hood adapted to cover said doors and door lifting means when the doors are in open position.

16. In a hopper car, a center sill, a transversely extending hood intersecting said sill, hoppers spaced longitudinally of said sill comprising inclined floor-sheets and longitudinally extending side hopper-sheets spanning the space between said inclined floor-sheets, shaft bearings secured to said side hopper-sheets, shafts in said bearings, doors adapted to close by gravity mounted on said shafts and extending from said inclined floor-sheets to the hood, a door lifting shaft interposed between the doors below the hood, and flexible means extending upwardly from the doors to said lifting shaft.

17. The herein described self-dumping coal car comprising a car body having an inclined bottom, a hood extending transversely of the car, the lower edge of the hood being spaced from the bottom to form a discharge chute, an arc-shaped valve pivotally mounted below the hood and resting normally upon said bottom closing said chute, center sills, a transverse shaft extending through said sills below the hood, and a flexible connection between the valve and the shaft, whereby on rotation of the shaft the valve will be lifted to open the discharge chute.

18. The herein described car comprising center sills, a body having inclined bottom sections spaced from each other longitudinally and transversely of the car, a transverse hood above said space within the car,

- the lower edges of the hood being spaced from said bottom sections to form discharge chutes, spaced pivot shafts extending transversely of the structure, a series of valves pivoted on said shafts and resting normally upon said bottom sections and movable upwardly in proximity to the lower edges of the hood, an operating shaft journaled above said pivot shaft and extending transversely 5 of the car through said sills, and connections between the operating shaft and the valves.
19. In a hopper car, the combination with a hopper of a segmental door pivotally mounted with its pivots on the side plates 15 of the hopper and disposed with its convex surface exposed toward an opening of the hopper for closing the same, the bottom wall of the hopper extending beneath the lower edge of the door for limiting downward 20 movement thereof, center sills, a shaft for elevating the door to a position out of the hopper opening extending through said center sills, and connections from the shaft to said door.
20. In a hopper car, a center sill, a plurality of spaced longitudinally extending 25

side hopper-sheets, a reinforcing member connected to said sill and to said hopper sheets, a transverse hood intersecting said sill above said reinforcing member, door-lifting means below said hood and adapted to be protected thereby, and a pair of rockable gravity closing doors adapted to be operated by said door-lifting means.

21. In a hopper car, a center sill, a plurality of spaced longitudinally extending side hopper-sheets, a continuous reinforcing member connected to said sill and to said hopper-sheets, a transverse hood intersecting said sill and some of said hopper-sheets 35 above said reinforcing member, door supporting rock shafts and door-lifting means below said hood and adapted to be protected thereby, and a pair of rockable gravity closing doors adapted to be operated by said 40 door-lifting means.

In witness whereof I have hereunto set my hand in the presence of two witnesses.

VICTOR M. SUMMA.
